UNITED STATES PATENT OFFICE

153,710

DESIGN FOR A CABINET SINK

Nena Lewis, Campbell, Ohio

Application April 2, 1947, Serial No. 138,110

Term of patent 7 years

(Cl. D33—19)

To all whom it may concern:

Be it known that I, Nena Lewis, a citizen of the United States, residing at Campbell, in the county of Mahoning and State of Ohio, have invented a new, original, and ornamental Design for a Cabinet Sink, of which the following is a specification, reference being had to the accompanying drawing, forming a part thereof.

The figure is a perspective view of a cabinet sink, showing my new design.

I claim:

The ornamental design for a cabinet sink, as shown.

NENA LEWIS.
